CRANK COUNTERBALANCE

Richard R. Bloss, Columbus, Ohio, assignor to
International-Stacey Corporation, Columbus,
Ohio, a corporation of Ohio

Application January 2, 1934, Serial No. 704,890

9 Claims. (Cl. 74—591)

My invention relates to crank counterbalances. It relates more specifically to crank counterbalances for use in connection with oil, gas or artesian wells. It has to do particularly with the provision of a crank counterbalance that may be used with the standard forms of cranks now commonly in use.

In the past, many types of crank counterbalances have been devised. However, in many instances, these crank counterbalances have been of such a nature as to require a specially-constructed crank. Also, in some instances, the means used for attaching the counterbalances to the crank arm has not been adequate to withstand the stresses and strains to which such a connecting means is subjected.

It is customary to provide the crank arm of well drilling or pumping mechanism with a plurality of openings adapted to receive a wrist pin by means of which the pitman of the mechanism may be attached thereto and at various locations therealong to vary the length of the pumping stroke, as is well understood by anyone familiar with the art. These cranks are usually provided in either one of two sizes, namely, a shorter crank arm having four wrist-pin holes or a larger one having six wrist-pin holes. In many cases, it is desirable to obtain a longer pumping stroke than it is possible to obtain by use of the four-hole crank arm. Heretofore, if this were desired, it was necessary to replace the said four-hole crank arm by the longer type having six holes. If the wrist pin of the pitman is mounted in the outermost hole of the six-hole type of crank arm, a much longer stroke of the pumping mechanism is produced than when it is disposed in the outermost hole of the four-hole type.

One of the objects of my invention is to provide a crank counterbalance which may be readily applied to and detached from a crank arm of a standard type now commonly in use.

Another object of my invention is to provide a crank counterbalance which may be used with the standard types of crank arms now commonly in use, either the shorter or the longer type, but which is particularly applicable for use with crank arms of the shorter four-hole type when it is desirable to obtain a greater pumping stroke than could be obtained by use of the four-hole crank alone.

Another object of my invention is to provide a crank counterbalance which is of such a type that it may be readily attached to or detached from a crank arm, and when attached to said crank arm, the means for attaching it thereto

will be fully adequate to resist the stresses and strains to which such a connection is subjected.

In its preferred form, my invention contemplates the provision of a counterbalance weight which is suspended in cooperative relation with the crank arm. The counterbalance weight structure embodies a main portion of suitable form which has means adjacent its upper portion adapted to firmly grip the lower end of the crank arm in order that the crank arm and the weight will be firmly attached together and will rotate together. The counterbalance weight also has a plurality of removable weights which may be mounted thereon to vary the counterbalance effect as desired. The counterbalance weight is adapted to serve in reality as an extension of the crank arm and means is provided for connecting the pitman of the pumping mechanism directly to the weight structure in order that a greater pumping stroke may be obtained than is possible when the pitman is connected to the crank arm at its outermost portion.

The preferred embodiment of my invention is shown in the accompanying drawings wherein similar characters of reference designate corresponding parts and wherein:

Figure 1 is a view of well pumping or drilling mechanism having a counterbalance made in accordance with my invention associated with the crank arm thereof, the crank arm being of the shorter four-hole type.

Figure 2 is a side elevation of a crank counterbalance structure made in accordance with my invention and showing how it is applied to the crank arm.

Figure 3 is a vertical section taken substantially on line 3—3 of Figure 2.

Figure 4 is a perspective view of a portion of the crank counterbalance and a portion of the lower end of the crank arm, illustrating in detail the means for embracing the lower end of the crank arm.

Figure 5 is a detail, in section, showing a part of the upper portion of the counterbalance weight and how the lugs adapted to grip the lower end of the crank arm fit into the edge of the counterbalance weight.

With reference to the drawings, I have shown in Figure 1 well drilling or pumping mechanism embodying a derrick 1 having a Samson post 2 disposed directly adjacent the lower end thereof in the usual manner. This Samson post 2 supports a walking beam 3 on its upper end which is pivotally connected thereto as indicated at 4.

One end of the walking beam 3 is connected to

a polished rod 5 which is connected to a sucker rod operating in the casing of the well. The opposite end of the walking beam 3 is connected to a pitman 6 in the usual manner. This pitman 5 may be connected to the crank arm 7 of the pumping mechanism or a counterbalance weight 8, as will be described more fully hereinafter.

From reference to Figure 3, it will be seen that the crank arm 7 is supported on the outer end 10 of a crank shaft 9. The outer end of this crank shaft is rotatably mounted in a bearing disposed on the upper end of a jack post 10. The crank arm 7 is of a standard type but, as will be explained more fully hereinafter, this crank arm 15 is of the shorter four-hole type.

The counterbalance weight 8 which is associated with the crank arm is more clearly illustrated in Figure 2. This counterbalance weight embodies a body portion 11 which is suspended 20 in cooperative relation with the lower end of the crank arm 7.

The means for suspending the counterbalance unit in cooperative relation with the crank arm embodies a pair of rods 12 having their lower 25 ends extending through slots 13 formed in the body portion 11 of the counterbalance weight at each end thereof. These slots have their outer sides open so that the entire rod may be slipped laterally outwardly therefrom. The rods 12 have 30 heads 15 formed on their lower ends. Cut-out portions 14 are provided in each end of the body portion 11 and are adapted to permit slipping of rods 12 into the innermost portions of slots 13, it being understood that inward movement of the 35 heads 15 will be permitted. On the rods 12 directly above heads 15, washers 15' are disposed. Each of these washers 15' is provided with a concave upper surface adapted to cooperate with a convex surface 15a against which the washers 40 will bear. Due to this concave surface on the washer and the convex surface on the shoulder, the washer substantially throughout its area will always contact with the shoulder even though the rod 12 might be swung to one side or the 45 other. Displacement of the rod to one side or the other will be necessary when the counterbalance is applied to crank arms of various lengths, as will be readily apparent. The inner sides of slots 13 are beveled downwardly and 50 outwardly as at 13' and then downwardly and inwardly as at 13a, in order to permit this adjustment of rods 12.

The rods 12 extend upwardly and inwardly and pass through slots 16 which are provided 55 in the cap structure 17. These slots 16 are similar to slots 13 and have open outer sides so that the rods may be swung laterally and outwardly therefrom. The cap structure 17 has a socket 18 formed in its under surface so that 60 it can fit over the upper end of the crank arm 7 and will be maintained in position thereon. When the counterbalance unit is in operative position as shown in Figure 2, the rods 12 extend a considerable distance up past the upper ends 65 of slots 16. The upper ends of the rods 12 have nuts 19 threaded thereon and directly below these nuts washers 19' are disposed. Each of these washers has a concave lower surface resting on a convex shoulder 18a. These cooperating concave and convex surfaces are provided 70 for the same reasons as those at the lower ends of the rods previously referred to. The inner sides of slots 16 are also downwardly and outwardly inclined as indicated at 16' and downwardly and 75 inwardly inclined as indicated at 16a for the

same purpose that the inner sides of slots 13 are similarly inclined. It will be apparent that by adjusting the nut 19, the counterbalance weight may be bodily raised or lowered as desired. The upper ends of rods 12, in Figure 2, 5 are shown as being cut off but it will be understood that they are of such length as to permit lowering of the counterbalance weight on a support where the weight will occupy a position in non-interfering relation with the lower end of 10 the crank arm.

In order to firmly attach the counterbalance weight structure to the crank arm 7, I provide the following structure. The upper edge of the body portion of the counterbalance weight is 15 provided with a groove formed therein, as illustrated at 20 in Figures 2, 3 and 5. This groove is of substantially less width than the thickness 20 of the body portion 11 and has beveled sides. When the crank counterbalance is adjusted into 25 operative position as shown in Figures 2 and 3, the extreme lower end of the crank arm will project slightly into this groove as illustrated at 21, and the beveled edge of the crank will wedge between the beveled sides of groove 20. Disposed 30 at each side of the lower end of the crank arm, is an adjustable lug member 22. These lug members are provided with downwardly projecting tongues 20' which fit into groove 20 and which operate therein. The tongues 20' projecting into 35 groove 20 preclude lateral displacement of lugs 22 and consequently prevent back and forth wobbling of the entire counterbalance as will be later seen. These lug members 22 are provided with outer surfaces 23 adapted to fit around the bevelled side edges of the crank arm 7. These outer surfaces 23 are shaped to correspond to the contour of the side edges of the lower portion of the crank arm 7 and are provided with grooves 40 adapted to receive said edges, as will be apparent from the drawings. The lug members 22 are movable laterally with relation to the crank arm. The tongues 20' will operate in the groove 20 and the lower surfaces of the laterally projecting portions 22' of the lugs will slide back and forth 45 on the surfaces 22a at each side of groove 20. It will be apparent that the central portion of the body portion 11 is cut out midway of its ends to receive the lugs 22 and other parts of the attaching means to be described. An up- 50 standing wall member 22b is provided behind the lugs 22 but in order to facilitate removal of the lug members such a wall member is not provided in front thereof. Thus, the lug members 22 may be adjusted laterally as described.

In order to force the lugs firmly in contact with the sides of the crank arm, I provide wedge members 24 which are disposed outside of the lug members 22. The outer surface of each of the lug members 22 is inclined downwardly and 60 outwardly as indicated at 25. The inner surface of each of the wedge members 24 is correspondingly beveled and its outer surface is straight as indicated at 26 and is adapted to abut a straight vertical wall 26' on the body portion 11. 65 Tongue and groove connections 31 are provided to preclude relative lateral displacement between lugs 22 and wedge members 24. Bolt members 27 pass upwardly through openings formed in the body portion 11 of the counterbalanced weight 70 and in the wedges 24. These bolts have nuts threaded on their upper ends. The heads 28 of the bolts are disposed in chambers 29 formed in the body portion of the counterbalance weight 75 which will cooperate with the heads 28 to prevent 75

bodily rotation of the bolts. These chambers 29 are of such a height as to permit dropping down of bolts 27 a considerable distance after the nuts are removed from the upper ends thereof and thereby facilitate removal of the wedge members. 5 Thus, the wedge members 24 and the lug members 22 may be entirely removed when desired, and since a wall similar to wall 22b is not disposed in part thereof, removal of the wedge members and lugs is facilitated. Due to the fact 10 that the wedge members and lugs are entirely removable, when it is desired to dispense with use of the counterweight, it may be dropped and need only be dropped slightly in order to dispose it 15 out of interfering relation with the end of the crank arm 1. Also, since the bolts 27 can be dropped, there will be no danger of the upper ends thereof interfering with rotation of the crank arm 1.

20 It will be apparent that when using this attaching means, the cap member 18 is first disposed on the upper end of the crank arm as illustrated in Figure 2, it being understood that the arm will occupy the position indicated. The nuts 19 on the upper ends of the rods 12 will then be adjusted to cause the counterbalance weight to be raised into a position shown in Figure 2 with the lower end of the crank arm extending slightly into the slot 20 and wedged therein. The lugs 22 25 are then disposed on each side of the lower end of the crank arm and the wedges 24 are properly positioned. It will be apparent that by screwing down the nuts on the upper ends of bolts 27, the wedge members will be forced downwardly and will wedge between the lugs 22 and the outer ends of slot 20. Consequently, the lugs 22 will be caused to firmly grip the lower end of the crank arm 1. A substantial space 30 will always remain between the lower end of each of 30 the wedge members and the bottom of slot 20, as shown in Figure 2. Thus, the nuts on the bolts 27 may be adjusted from time to time to maintain the lug members 22 in firm contact with the crank arm.

35 It will be apparent that the lugs 22 gripping the sides of the crank arm 1, will exert their force against such crank in a horizontal direction. Also, the rods 12 pulling up on the weight 8 will cause wedging of the lower end of the crank arm in the groove 20 and will aid in keeping the lower end of the crank arm seated between lugs 22. In other words, both a horizontal and a vertical wedging action are produced.

40 The body portion of the counterbalance weight 55 is provided with sets of weights 32 and 33 which are suspended therefrom by means of bolts 34. The bolts 34 have heads 35 formed on their lower ends which fit into sockets formed in the lowermost weight 36 in such a manner that the heads 45 cannot turn. These bolts extend upwardly into openings 37 formed in the body portion of the counterbalance unit. Passages 38 (Figure 5) extend laterally from the openings 37 adjacent their upper ends in order to permit access to nut members 39 threaded on the upper ends of bolts 34.

45 A plurality of weight members 40 may be disposed between the lowermost weight member 36 and the body portion 11. The adjacent weights 50 are provided with bosses 40' which fit into sockets in the other of the weights in order to aid in precluding relative lateral displacement of the weights. These weight members are provided 55 with U-shaped slots (not shown) which will fit 60 around the bolts 34. Thus, the intermediate 65 weights 40 may be removed or replaced as desired without completely removing the bolts 34 or disturbing the lowermost weights 36. When the desired weights are in position the nuts 39 may be screwed down on the bolts 34 to tightly clamp 70 all of the weights in position. In Figure 5 it will be seen that opening 37 extends upwardly a considerable distance. Thus, if some of the weights 40 are removed, the nut 39 may be adjusted to cause bolt 37 to move upwardly a sufficient distance until all the weights are tightly clamped together.

75 As previously stated, the crank arms are usually provided with a plurality of openings spaced therealong in order that the pitman may be attached thereto at various points therealong and thus vary the pumping stroke, as will be well understood by anyone familiar with the art. Thus, the crank arm 1 is provided with a plurality of spaced openings 41 adapted to receive the 20 wrist pin which is used for connecting the pitman thereto.

80 It is well known to a person familiar with this art that sometimes it is desirable to obtain a longer pumping stroke than could possibly be obtained by use of a four-hole crank arm of the type illustrated in the drawings. Previously, if this was the case, it was necessary to replace the four-hole type of crank arm by a six-hole type, which is considerably longer. However, I have 85 provided a counterbalance weight which makes this unnecessary and which can be used with the shorter four-hole type and by which it will be possible to obtain a longer pumping stroke than is possible with the shorter crank arm alone. 35

85 It will be apparent from an examination of the drawings that when the counterbalance unit is in operative position and is attached to the crank arm, the body portion 11 thereof in reality serves as a continuation of the crank arm. 40 It is contemplated in my invention to provide this body portion 11 with an opening 41' adapted to receive the wrist pin of the pitman structure when it is desired to obtain a maximum pumping stroke. This opening 41' is so formed that when 45 the counterbalance unit is in operative position it will be approximately in alignment with the openings 41 in the crank arm 1. Thus, when desired, the wrist pin may be disposed in this opening and, consequently, the pitman 6 will be 50 connected directly to the weight structure 8. Of course, if desired, more than one opening could be formed in the body portion of the weight structure. This renders unnecessary the replacement of the short four-hole crank arm 1 by a 55 six-hole crank arm of greater length in order to get a maximum pumping stroke of adequate length. The length of the crank arm is increased by the distance "A" illustrated by the arrows in Figures 3 and 4. 60

65 It will be apparent from the above description that I have provided a counterbalance unit having many desirable features. This counterbalance unit may be readily applied to crank arms of the standard types and may be readily detached therefrom. The attaching means is of such a type that it will adequately resist all stresses and strains to which it might be subjected. Due to the fact that the counterbalance weight serves as an extension of the crank arm 70 and has a means for connecting the pitman directly thereto, a maximum pumping stroke of greater length may be obtained. Thus, it will be possible by using this counterbalance unit with 75 crank arms of the shorter four-hole type to se-

cure a maximum pumping stroke of much greater length than could be obtained by use of the four-hole type of crank arm alone.

Of course I have used the terms "four-hole type" and "six-hole type" of crank arms for illustrative purposes only and I do not intend to be limited thereby.

Having thus described my invention, what I claim is:

- 10 1. In combination with the crank arm of a well pumping mechanism, means for suspending a counterbalance weight structure in cooperative relation with said crank arm, said means including a cap member, a plurality of rods having one of their ends connected to said cap member and their opposite ends attached to said weight structure, a pair of lugs disposed on the upper portion of said weight structure and adjustable laterally thereof into gripping relation with the lower portion of said crank arm, and a pair of wedge members mounted on the upper portion of said weight structure and adapted to maintain said lugs in gripping relation with said crank arm.
- 25 2. In combination with the crank arm of a well pumping mechanism, a counterbalance weight, means for suspending said counterbalance weight in cooperative relation with said crank arm, said means including a cap member which fits over the upper end of said crank arm, a plurality of rods having one of their ends connected to the cap member and their opposite ends connected to said counterbalance weight, the one end of each of said rods fitting into an open-ended slot in said cap member and the opposite end of each of said rods fitting into an open-ended slot in said counterbalance weight, said rods being adjustable to cause movement of the weight radially of said crank arm, said weight having a recessed portion in its upper edge, a slot formed in the bottom of said recess, the lower end of said crank arm fitting into said slot when the rods are properly adjusted, a lug disposed in said slot at each side of said crank arm for gripping the lower end of said crank arm comprising a pair of wedge members each of which is disposed between one of said lugs and the corresponding end of said recess, and adjustable means for causing said wedge members to be tightly wedged in position and to cause said lug members to grip said crank arm.
- 40 3. In combination with the crank arm of a well pumping mechanism, a counterbalance weight, means for suspending said counterbalance weight in cooperative relation with said crank arm, said means including a cap member which fits over the upper end of said crank arm, a plurality of rods having one end connected to the cap member and the other end connected to said counterbalance weight, the one end of said rods fitting into an open-ended slot in said cap member and the opposite end of each of said rods fitting into an open-ended slot in said counterbalance weight, said rods being adjustable to cause movement of the weight radially of said crank arm, a slot formed in the upper edge of said weight, the lower end of said crank arm fitting into said slot when the rods are properly adjusted, a lug disposed in said slot at each side of said crank arm for gripping the lower end of said crank arm comprising a pair of wedge members each of which is disposed between one of said lugs and the corresponding end of said recess, and adjustable means for causing said wedge members to be tightly wedged in position and to cause said lug members to grip said crank arm.
- 55 4. In combination with the crank arm of a well pumping mechanism, a counterbalance weight, means for suspending said counterbalance weight in cooperative relation with said crank arm, said means including a cap member which fits over the upper end of said crank arm, a plurality of rods having one end connected to the cap member and the other end connected to said counterbalance weight, the one end of said rods fitting into an open-ended slot in said cap member and the opposite end of each of said rods fitting into an open-ended slot in said counterbalance weight, said rods being adjustable to cause movement of the weight radially of said crank arm, a slot formed in the upper edge of said weight, the lower end of said crank arm fitting into said slot when the rods are properly adjusted, a lug disposed in said slot at each side of said crank arm for gripping the lower end of said crank arm, and means for causing said lugs to firmly grip said crank arm, said means comprising a pair of adjustable wedge members.
- 70 5. In combination with the crank arm of a well pumping mechanism, a counterbalance weight, means for suspending said counterbalance weight in cooperative relation with said crank arm, said means including a cap member which fits over the upper end of said crank arm, a plurality of rods having one end connected to the cap member and the other end connected to said counterbalance weight, the one end of said rods fitting into an open-ended slot in said cap member and the opposite end of each of said rods fitting into an open-ended slot in said counterbalance weight, said rods being adjustable to cause movement of the weight radially of said crank arm, a slot formed in the upper edge of said weight, the lower end of said crank arm fitting into said slot when the rods are properly adjusted, a lug disposed in said slot at each side of said crank arm for gripping the lower end of said crank arm comprising a pair of wedge members each of which is disposed between one of said lugs and the corresponding end of said recess, and adjustable means for causing said wedge members to be tightly wedged in position and to cause said lug members to grip said crank arm.
- 75 6. An attachment for the crank arm of well pumping mechanism comprising a counterbalance weight structure adapted to be disposed in cooperative relation with said crank arm, said weight structure having a recess formed in its upper edge, a slot formed in the bottom of said recess, a pair of lugs disposed in said recess and adjustable therewith, said lugs being adapted to grip the lower end of said crank arm, means for maintaining said lugs in gripping relation to the crank arm, said means comprising wedge members each of which fits between one of said lug members and the corresponding end of said recess.

7. An attachment for the crank arm of a well pumping mechanism comprising a counterbalance weight structure adapted to be disposed in cooperative relation with said crank arm, said weight structure having a recess formed in its upper edge, a slot formed in the bottom of said recess and adjustable therewith, said lugs being adapted to grip the lower end of said crank arm, means for maintaining said lugs in gripping relation to the crank arm, said means comprising wedge members each of which fits between one of said lug members and the corresponding end of said recess.

8. An attachment for the crank arm of a well pumping mechanism comprising a counterbalance weight structure adapted to be disposed in cooperative relation with said crank arm, a plurality of lugs disposed on said weight structure and being slidable bodily and laterally along said weight structure into and out of gripping relation with the crank arm, means for maintaining said

70
75
75

lugs in gripping relation to the crank arm, said means comprising wedge members each of which fits between one of said lug members and an abutment formed on said weight structure.

5 9. In combination with the crank arm of a well pumping mechanism, a counterbalance weight, means for suspending said counterbalance weight in cooperative relation with said crank arm, said means including a member from which the weight 10 is suspended, a plurality of rods having one end connected to said member and the other end connected to said counterbalance weight, said rods being adjustable to cause movement of the

weight radially of said crank arm, one end of each of said rods fitting into an open-sided slot in said member and the opposite end of each of said rods fitting into an open-sided slot in said counterbalance weight, said member having a convex portion formed thereon adjacent the upper end of each slot formed therein and said weight having a convex portion formed thereon adjacent the lower end of each slot formed therein, each of said rods being provided with a member adjacent each end having a concave portion for cooperating with one of said convex portions. 10

RICHARD R. BLOSS.
